[57] **CLAIM**

The ornamental design for the roasting rack, as shown
and described.

DESCRIPTION

FIG. 1 is a top perspective view of a roasting rack
showing my new design;

FIG. 2 is an enlarged top plan view thereof;

FIG. 3 is a bottom plan view thereof;

FIG. 4 is a front elevational view, the rear elevational
view being a mirror image thereof; and,

FIG. 5 is a left side elevational view on a reduced scale,
the right side elevational view being a mirror image
thereof.
